(57) **CLAIM**

The ornamental design for a switch plate, as shown and described.

DESCRIPTION

FIG. 1 is a front view of the switch plate;
FIG. 2 is a back view of the switch plate;
FIG. 3 is a top view of the switch plate;
FIG. 4 is a bottom view of the switch plate;
FIG. 5 is a left view of the switch plate;
FIG. 6 is a right view of the switch plate;
FIG. 7 is a perspective view of the switch plate; and,
FIG. 8 is a second perspective view of the switch plate.

1 Claim, 4 Drawing Sheets
